AIR COMPRESSOR CONTROLLER

Burton E. Shaw, Bristol, Ind., assignor to Penn Electric Switch Co., Goshen, Ind., a corporation of Indiana

Application April 4, 1938, Serial No. 199,905

5 Claims. (Cl. 200—83)

One of the objects of my present invention is to provide a comparatively simple, rugged and durable control device for heavy duty operation in the control of air compressor motors and the like.

Another object is to provide a control device comprising a housing in which is mounted an automatic pressure responsive switch and a magnetic unloader for the air compressor, the parts being so arranged that compactness is secured and at the same time all adjustments are readily accessible when the housing is open.

A further object is to provide an air compressor switch having a partition in the switch housing for dividing the current carrying contacts from the mechanical mechanism of the housing, the partition being adjacent the top of the housing and having mounted thereon stationary contacts which face outwardly so that they are readily accessible for removing, cleaning and replacing purposes.

Another object is to provide a bridging member having contacts for coaction with the stationary contacts which bridging member is also readily accessible for removal, cleaning and replacement, the structure being such that the bridging contacts float on contact carrying arms so that they are thereby suspended in a balanced manner on the arms.

Still another object is to provide shoulders on the arms against which the bridging members engage, spring means being used to cause such engagement and special washers coacting with T-head ends of the contact carrying arms to facilitate removal of the bridging members from the arms.

A further object is to provide a V-over roller connection between an actuating arm which is actuated by a pressure responsive diaphragm and a switch arm which carries the contact carrying arms, a differential spring being used to retain the spring and V-over roller connection in relative coaction and an adjusting screw for the differential spring being arranged so that an operating portion thereof is readily accessible for changing the tension of the spring.

A further object is to provide the actuating arm and the switch arm substantially spaced from each other so that between them a range spring can be mounted, which has an adjusting screw also readily accessible, the V-over roller connection including a link mounted at one side of the housing so that there is a substantial space between the link and the other side of the

housing to receive a magnetic unloader valve actuator.

Still a further object is to provide unloader mechanism including an unloader valve mounted on the exterior of the housing and a magnetic unloader valve mechanism mounted on the interior thereof, this actuator being formed inexpensively of an enclosing pole of cast iron or the like with a solenoid mounted therein and a comparatively heavy core movably mounted in the solenoid for actuating the unloader valve through the medium of a valve lever mounted to extend between the interior and the exterior of the housing.

As a further object of my invention I provide an air compressor controller in which all the parts are so designed and related to each other that they can be mounted in a minimum of space within a controller housing, whereby the overall dimensions of the controller may be kept small and none of the parts interfere with each other either during assembly or in operation after assembly.

Although the invention is susceptible of a variety of embodiments, it is unnecessary to fully describe and illustrate more than one in order to give a full understanding of the invention both from its structural and functional standpoints. Accordingly, I have illustrated a preferred and desirable embodiment of the invention in the accompanying drawings forming a part of this specification and throughout the views of which like reference characters refer to the same parts.

Figure 1 is a side elevation of an air compressor controller embodying my invention.

Figure 2 is an enlarged sectional view thereof on the line 2—2 of Figure 1 showing one of the contact bridging members removed.

Figure 3 is a sectional view on the line 3—3 of Figure 2.

Figure 4 is an exploded perspective view of the contact mechanism of the control switch in my control structure.

Figure 5 is a sectional view on the line 5—5 of Figure 3 showing a cross section through a magnetic unloader valve actuator which is omitted from the showing in Figure 3.

Figure 6 is an enlarged sectional view on the line 6—6 of Figure 1 showing the unloader valve and showing diagrammatically an air compressor system connected therewith.

Figure 7 is a sectional view on the line 7—7 of Figure 3.

Figure 8 is a sectional view on the line 8—8 of Figure 3; and

Figure 9 is a sectional view on the line 9—9 of Figure 3 to show the connection of a differential spring with its adjusting screw.

On the accompanying drawings I have used the reference character H to indicate generally a controller housing. The housing H comprises a back 10, a bottom 12 and a pair of sides 13 and 14. 10 The housing also includes a cover member C having a top 15 and a front 16. The cover member C is normally retained in position by screws 17 which, after removal, permit the cover member to be removed thereby exposing both the top and 15 front of the mechanism within the housing H.

A partition P is mounted within the housing H. This partition is made of insulating material and has a plurality of contact barriers 18 extending upwardly therefrom. Between the 20 barriers 18 there is a series of stationary contacts 19 and another series of stationary contacts 20. As illustrated there are three contacts in each series, the controller being for a three-wire circuit. Obviously it can be provided for one or 25 two wires or for four or more wires if desired.

The stationary contacts 18 are adapted to be bridged by bridging members 21 when the switch is in closed position. The members 18, 20 and 21 have appropriate contact points which 30 are shown coacting with each other in Figure 3. The partition P is retained in position at the back of the housing H by a pivot bolt 22 extending through perforated ears 23 thereof. At the front of the housing, screws 24 extend through the sides 13 and 14 and into the partition.

Pivottally mounted on the pivot pin 22 is a switch arm S. The switch arm S comprises a cross bar 25 of insulating material and a pair of L-shaped side plates 26 and 27. The side 40 plates 26 and 27 are secured to the ends of the bar 25 as by screws 28. The upstanding portions of the L-shaped arms 26 and 27 are provided with hubs 29 (see Figure 8) oscillatable on the pivot pin 22. The pivot pin is retained 45 in position relative to the housing H by a nut 30.

The L-shaped arm 26 has an extension 31 toward the right from the bolt 22. A bracket 32 is riveted as at 33 to the inner face of the arm 26 (see Figure 3). The right hand ends 50 of the extension 31 and the bracket 32 are provided with a pivot pin 34 and enlarged openings 35. A link 36 has a pin 37 extending through the enlarged openings 35 and is connected by a pair of links 38 to the pivot pin 34. The links 55 38 have holes therein adjacent their ends for the pins 34 and 37. The links 38, together with the openings 35 and the pin 37, provide a lost motion connection by reason of the play of the pin 37 in the enlarged openings 35, the purpose 60 of which will hereinafter appear.

The arm 26 and the bracket 32 are provided with an arcuate slot 39 (formed with the axis of the bolt 22 as a center) which receives a stop pin 40 projecting from the side 13 of the housing H. The pin 40 serves to limit the swinging movement of the switch arm S about the pivot bolt 22.

Mounted against a diaphragm plate 41 on the bottom 12 of the housing H is a pressure diaphragm 42. It is retained in position on the bottom 12 by screws 44. A boss 45 is provided on the diaphragm chamber 43 which is threaded to make connection with compressed air piping or tubing in the usual manner.

75 An actuating pin 46 rests against the dia-

phragm 43 and is retained thereagainst by a range spring 47. The spring 47 is interposed between washers 48 and 49. The washer 48 has at each side a pair of arms 50 engaging in reduced portions 51 of a pin 52 (see Figure 5). The pin 52 serves as a thrust connection between the pin 46 and the washer 48.

The washer 49 is slidably mounted on a range adjusting screw 53 carried by a cross member 54 secured to the sides 13 and 14 of the housing H by screws 55. A nut 56 on the screw 53 may be rotated for adjusting the tension of the spring 47.

The ends of the pin 52 extend through a U-shaped actuating arm 57. The arm is pivoted 15 on a pin 58 which in turn is supported by a bracket 59. An L-shaped extension 60 is riveted to the cross member of the U-shaped actuating arm 57 and is formed to provide a bifurcated portion in which a roller 61 is mounted. The roller 61 has its bore receiving a pin 62 carried by the actuating arm extension 60. The roller is provided with a pair of side flanges 63.

The link 36 has a V-shaped end 64 adapted to coact with the roller 61 to provide a "V-over roller" type of connection between the actuating arm and the switch arm. For retaining the parts of the V-over roller connection in coaction with each other, I provide a differential 30 spring 65. One end of the spring 65 is connected to a perforated ear 66 of the link 36 while the other end is connected to a nut 67 (see Figure 9) into which a differential adjusting screw 68 is threaded. The screw 68 extends rotatably through a perforated ear 69 of the cross bracket 54 and has an operating portion thereon consisting of a head 70. To retain the head 70 in any position to which it is rotated, a U-shaped 40 spring 71 engages opposite sides thereof (as shown in Figure 7) and the spring has a clip portion 72 as shown in Figure 3 extending back of the ear to retain the spring in position and against rotation relative to the ear 71.

The bridging members 21 are mounted on the 45 switch arm cross bar 25 in the following described manner: Contact carrying arms 73 extend upwardly from the bar 25 and are electrically insulated from each other by the bar. The arms 73 as shown in Figure 4 are provided 50 with shoulders 74 and with T-heads 75. The contact members 21 are provided with slots 76 which loosely receive the arms 73 above the shoulders 74. Springs 77 are mounted on the arms 73 after the bridging members 21 are positioned thereon and after washers 78 are positioned on the arms against the bridging members.

For retaining the springs 77 in position and backing them up so that they tend to retain 60 the bridging members 21 against the shoulders 74, I provide spring washers 79. These washers are provided with slots 80 and depressions 81 transversely of the slots. The washers 79 are associated with the T-heads 75 by permitting 65 the T-heads to be extended through the slots 80 and then rotating the washers a quarter turn so that the springs urge them outwardly when the depressions 81 coact with the T-heads as shown in Figure 2. Thus the washers 79 are 70 readily removable whereupon the spring 77 and the washer 79 can also be removed from the contact carrying arm 73. This permits removal of the bridging members 21 so that their contact points can be readily cleaned and so that 75

the contact points of the stationary contacts 19 and 20 are exposed for ready cleaning.

On the side 14 of the housing H, I provide a bracket 82. An unloader valve V is mounted on this bracket and may comprise the following parts, as illustrated in Figure 6. A valve body 83 is secured to the bracket 82 as by lock nuts 84. An air inlet 85 is provided in the body 83 and an unloader chamber connection is provided by a passageway 86. Communication between the passageways 85 and 86 may be controlled by a valve member 87 while communication between the passageway 86 and a passageway 88 which communicates with atmosphere 15 is provided by a valve member 89. The valve member 89 has a resiliently mounted operating pin 90.

The valve lever 91 is pivoted on a pivot pin 92. The pivot pin 92 is carried by a bracket 93 extending from the side 14 of the housing H adjacent an opening 94 therein. The valve lever extends through this opening and has a short end positioned under the operating pin 90 as shown in Figure 8.

25 A magnetic unloader valve actuator is provided in the form of a pole 95, a solenoid 96 and a core 97. The pole 95 is of the enclosing type or, in other words, substantially surrounds the solenoid 96. It is preferably made of soft 30 cast iron and has a stop member 98 secured to the top thereof by a cap screw 99 as shown in Figure 8.

A washer 100 is secured to the lower end of the enclosing pole 95 for retaining the core 97 against 35 dropping out of the bore of the solenoid. The core 97 is adapted to engage the long end of the valve lever 91.

As shown diagrammatically in Figure 6 the unloader valve V is adapted to be connected in 40 an air compressor system in which there is a tank T and an air compressor AC. The compressor AC supplies compressed air to the tank and the tank is connected with the passageway 85 of the valve V. Normally the valve is in the 45 position shown in Figure 6 when the system is in operation, as the solenoid 96 is energized when the motor circuit is energized and the long end of the valve lever 91 is thereby held raised by a spring 87a in the valve V. When the circuit 50 of the switch is open, both the air compressor and the solenoid 96 are de-energized, thus permitting the valve member 89 to close and the valve member 87 to open. Thereupon air flows from the passageway 86 thru piping 101 to an 55 unloader chamber 102 of the air compressor for holding the intake valve 103 thereof off its seat. This unloads the air compressor by permitting it to "breathe" through the intake valve while the compressor is getting up to speed. As soon 60 as the air compressor is started, however the solenoid 96 is energized for closing the valve 87 and opening the valve 89 so that air in the unloader chamber 102 gradually escapes to atmosphere and thereby permits normal functioning 65 of the intake valve by the time the air compressor has attained its normal speed.

The design of my air compressor switch has solved several problems. In order to provide a powerful actuating device for the unloader valve particularly when a three-way valve, as shown in Figure 6, is used, and yet have a structure which can be economically made, a relatively heavy and large pole member 95 of cast iron has been provided and a relatively heavy 70 core member 97 has also been provided. This

heavy core member is necessary in order to effect positive opening of the valve 87 against tank pressure and such opening is facilitated by the leverage of the lever 91. When a heavy core member is provided, obviously a strong pull 5 must be exerted thereon to lift it. By providing a substantially closed path for the magnetic flux of the solenoid 96 through the pole member 95 as I have it shaped and by providing the stop extension 98, I am able to exert considerable pull 10 on the core 97 when the solenoid is energized without having to go to expensive laminated construction.

By arranging the switch mechanism in the housing H as disclosed with the actuating arm 15 57 adjacent the bottom thereof, the link 36 adjacent one side and the partition P and the switch arm S adjacent the top, I provide considerable space within the housing in which 20 the relatively large magnetic unloader valve actuator can be mounted. At the same time the parts have been so designed that ready access 25 can be had to the contacts for cleaning them and the differential and range adjustment screws can be readily adjusted when the cover member C 30 has been removed from the housing. The construction shown in Figure 4 facilitates removal of the bridging members 21 so that all the contacts of the switch are thereby accessible for cleaning.

Some changes may be made in the construction and arrangement of the parts of my controller without departing from the real spirit and purpose of my invention, and it is my intention to cover by my claims, such modified 35 forms of structure or use of mechanical equivalents as may be reasonably included within their scope.

I claim as my invention:

1. In an air compressor switch, a switch housing, a partition therein spanning the distance between two opposite walls of said housing and serving as a spacer therebetween, a switch arm mounted for swinging movement toward and away from the bottom of said partition and having contact carrying arms extending through an opening in the partition, stationary contacts mounted on the top of said partition, bridging members having contacts for coaction with said stationary contacts and carried by said contact carrying arms, said contact carrying arms having shoulders for said bridging members to normally rest against, resilient means constraining said bridging members to rest against said shoulders, means for limiting the movement of said switch arm to a position with said shoulders spaced from said bridging members when the switch arm is in closed circuit position, and air pressure responsive means for swinging said switch arm toward and away from said partition. 55

2. In an air compressor switch, a switch housing, a switch arm mounted for movement therein and having contact carrying arms, stationary contacts mounted in said housing, bridging members having contacts for coaction with said stationary contacts and carried by said contact carrying arms, resilient means constraining said bridging members to engage said stationary contacts when the switch arm is in closed circuit 70 position, said resilient means comprising springs encircling the contact carrying arms and washers for retaining said springs in position, said contact carrying arms comprising flat blades having T-heads and side lugs spaced below said 75

heads, said washers having slots through which said T-heads may be extended and having depressions transversely of said slots to receive said T-heads whereby said washers may be associated with the contact carrying arms by extension of the T-heads through said slots and rotation of the washers thereafter for said depressions to contact with said T-heads, said washers serving as back stops for said springs, said springs, in the open circuit position of said switch arm, engaging said bridging members with said side lugs of said contact carrying arms, said bridging members being slotted and loosely receiving said contact carrying arms so that after removal of said washers and springs, said bridging members may be removed from said contact carrying arms to permit unobstructed access to said stationary contacts and air pressure responsive means for swinging said switch arm toward and away from said partition.

3. In a control switch, a cuboid switch housing comprising four walls and a cover providing two walls, a partition in said housing, said partition connecting two of said four walls together and thereby retaining proper spacing between them, a switch arm mounted for swinging movement toward and away from said partition and having a contact carrying arm extending through an opening in the partition, stationary contacts mounted on said partition, a bridging member having contacts for coaction therewith and carried by said contact carrying arm, said contact carrying arm having an integral shoulder for said bridging member to normally rest against, resilient means constraining said bridging member to rest against said shoulder, means for limiting the movement of said switch arm to a position with said shoulder spaced from said bridging member when the switch arm is in closed circuit position, and condition responsive means for swinging said switch arm toward and away from said partition.

4. In an air compressor switch, a substantially rectangular housing, a switch arm therein adja-

cent the top thereof, contacts operatively connected with said switch arm and means for operating said switch arm comprising a pressure responsive element on the bottom of said housing adjacent the front thereof, and an actuating arm extending along one horizontal corner of said housing for actuation by said pressure responsive element, a link extending along one of the vertical corners of said housing, connected with said switch arm and having a V-over roller connection with said actuating arm, a differential spring retaining said V-over roller connection in cooperating relationship and extending at substantially right angles from said link along one side of said housing to the front thereof, a differential adjuster screw for adjusting the tension of said differential spring, a range spring for said actuating arm and extending substantially parallel to said link and adjacent said front of said housing, and a range adjuster screw therefor, said differential and range adjuster screws having operating portions adjacent said front of said housing.

5. In an air compressor switch, a substantially rectangular housing, a switch arm therein adjacent the top thereof, contacts operatively connected with said switch arm and means for operating said switch arm comprising a pressure responsive element on the bottom of said housing and an actuating arm adjacent one side of said housing for actuation by said element, a link connected with said switch arm, extending along said side of said housing and having a V-over roller connection with said actuating arm, a differential spring retaining said V-over roller connection in coacting relationship, a differential adjuster screw for adjusting the tension of said differential spring, a range spring for said actuating arm, a range adjuster screw therefor, said actuating arm having its V-over roller connection at one of the vertical corners of said housing, said link being adjacent and extending along said corner of said housing.

BURTON E. SHAW.
